BY

A. B. McCall
ATTORNEY.

UNITED STATES PATENT OFFICE.

EMMETT V. POSTON, OF SPRINGFIELD, ILLINOIS.

MACHINE FOR VENEERING BRICK.

Application filed June 21, 1927. Serial No. 200,349.

My invention relates to the class of machines adapted to be used for veneering and texturing clay columns before firing, or brick units before or after firing, an object of this invention being particularly to provide a means of mechanically or centrifugally blasting granular veneer materials so as to project them forcefully and embed and impact them into the exposed faces of the brick body 10 as the brick body, either in column form or in the unit brick, moves along preferably on a conveyor.

An object of my invention is to provide a machine by which I may be able to achieve 15 the process of veneering and texturing brick for which I have filed application for patent bearing Serial Number 200,346 filed June 21, 1927.

A further object of my invention is to 20 provide a means for successfully projecting mechanically the granular veneer materials forcefully into the plastic faces of the brick column or unit brick, so as to make them strike approximately at right angles to the 25 brick face into which they are embedded.

I accomplish the purpose of my invention in the machine described in the following specifications, recited in the claims and illustrated in the accompanying drawings.

Like reference numerals indicate like parts in the several figures.

Referring to the drawings—

Figure 1 is an elevation disclosing to view the machine of my invention and showing 35 in this view a section of the clay column as well as the broken portions of the carrier tubes in my invention.

Fig. 2 is a section, 2—2, Fig. 1, of a portion of my machine for veneering brick.

Fig. 3 is a section, 3—3, Fig. 1, of a portion 40 of my machine for veneering brick.

Fig. 4 is a horizontal section, 4—4, Fig. 1, of a portion of my machine for veneering brick.

Referring in detail to the structure of my 45 brick veneering machine and the method of operating the same, I conduct the veneer materials 2 from a hopper 1 through a plurality of conveyors 3, 4, 5 and 6, which may be of any suitable height, or may be positioned so 50 as to convey the veneer materials in any suitable conducting manner to the mechanical paddle blasting drums 13, 14 and 15, which are each provided with propeller blades adapted to rotate with the drum for forcefully blasting the granular veneer ma-

terials to project and substantially embed and impact them into the exposed faces of the plastic clay ribbon or units of brick made therefrom.

By my machine I accomplish the projection of these veneer particles at right angles to the face of the ribbon of brick material in order that the veneer materials may not easily glance off, but more certainly penetrate the face of the plastic brick body.

Gates 8 for the regulation of the supply of veneer materials from hopper 1 are manually controlled through shaft 7, while at 9 and 9' are shown opposite ends of a manual method of controlling a scraper (not shown) for a rotating drum within hopper 1 adapted to keep the granular veneer particles moving and yet avoid congestion of material near the outlet opening.

A conveyor 10 carries the ribbon of brick material 11 from the die 21 and as the ribbon of brick material moves along it passes the point where the veneering materials are forcefully projected into the exposed faces thereof, as is shown in Fig. 1.

It will be noted in Fig. 2 that a guard 12 tends to limit the veneer materials 2 in their forcefully directed and blasted movement toward the clay column 11.

Pulley 18 is connected to a source of power for rotating shaft 16 carrying drum 13, and incidentally rotating drums 14 and 15 through bevel gearing, as is shown in Fig. 1.

It will be noted that a belt 22 may operate to control conveyor 10 in its movement. A frame structure 17 is adapted to support the rotating drums 13, 14 and 15, while a closure member 19 is adapted to confine the dust and dirt and the like to the point of operations to avoid inconveniences to the workmen.

As the veneer materials are released from hopper 1 through gates 8 to pass through tubes 3, 4, 5 and 6, they are brought into contact, by gravity or otherwise, with speedily rotating paddle blasting drums 13, 14 and 15, which by reason of their speed rotation, project with force the granular particles at right angles into the plastic face of column 11, or brick units while in plastic condition.

Pulley 20 is connected with a source of power for rotating the drum within hopper 1. Shaft 16, carrying paddle blasting drum 13, is driven from a source of power through

pulley 18 and connected through gears so as to simultaneously rotate paddle blasting drums 14 and 15. Shaft 16 also carries the driving wheel connected by belt 22 to the roller supporting conveyor 10.

It will be observed that guard 12, see Figs. 3 and 4, is adapted to limit the movement of the veneer particles 2 so as to aid in directing them perpendicularly and force-
10 fully to be projected into the plastic adjacent face of the clay column or brick unit carried by the conveyor, while numeral 23 indicates a pipe connection adapted to conduct water to a point where it may moisten
15 the granular veneer particles before they come in contact with the clay column.

To those skilled in the brick manufacturing industry, it will be evident that other mechanical methods of veneering may be
20 used, but the preferred arrangement of my invention is disclosed in the specifications herewith and recited in the claims which follow:

Having thus disclosed the machine of my
25 invention, what I claim is:

1. A machine for substantially project-

ing and embedding granular veneer materials approximately at right angles into the exposed faces of a plastic clay body by means of mechanical rotating paddle blasting or centrifugal projecting of the materials, and means for moistening the materials.

2. A machine for substantially projecting and embedding granular veneer materials at right angles into the exposed faces of a plastic clay body by means of mechanical rotating paddle blasting of the materials, including a hopper for holding the supply of veneering materials, rotatable blasting drums for forcibly projecting said materials into the exposed faces of the brick body, a plurality of conducting tubes adapted to conduct the materials from the hopper to the blasting drums, means for moistening said materials, and means for operatively connecting said paddle blasting drums with a source of driving power.

In witness whereof, I have hereunto set my signature this 20th day of June, A. D., 1927.

EMMETT V. POSTON.
